[57] **CLAIM**

The ornamental design for a protective cap for pop-up lawn sprinklers, as shown and described.

DESCRIPTION

FIG. 1 is a perspective view of a protective cap for pop-up lawn sprinklers showing our new design;

FIG. 2 is a top plan view thereof, on an enlarged scale;

FIG. 3 is a side elevational view thereof, all sides being

identical, on an enlarged scale;

FIG. 5 is a side elevational view thereof, the cap rim

shown in an open position.

FIG. 1

FIG. 2

FIG. 5

FIG. 4
